COMMUTATOR RECONDITIONING DEVICE

Adolph L. Baurhenn, New York, N. Y.

Application February 19, 1941, Serial No. 379,677

2 Claims. (Cl. 82—34)

This invention relates to a commutator reconditioning device, and has for the primary object the provision of a device of this character which may be readily adapted to a lathe to quickly and accurately cut the insulation between the commutator bars of an electric armature supported by the lathe and thereby bring the grooves between the bars to a proper depth and to remove any abrasions or particles that may be on the sides of the commutator bars after the latter have been turned down in the reconditioning operation, also by changing the cutting tool of the device the latter may be successfully employed for turning down the brush faces of the commutator bars prior to the operation of cutting the insulation and deepening the grooves of the commutator.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a fragmentary top plan view showing a portion of a lathe supporting an electric armature and equipped with a reconditioning device constructed in accordance with my invention.

Figure 2 is an end elevation illustrating the device mounted on a portion of the lathe.

Figure 3 is a side elevation illustrating the device.

Figure 4 is a vertical sectional view illustrating a supporting post of the device.

Figure 5 is a sectional view taken on the line 5—5 of Figure 1.

Figure 6 is a perspective view illustrating a spacer.

Figure 7 is a sectional view taken on the line 7—7 of Figure 1.

Figure 8 is a detail sectional view taken on the line 8—8 of Figure 1.

Figure 9 is a top plan view illustrating a modified form of my invention.

Figure 10 is a sectional view taken on the line 10—10 of Figure 9.

Figure 11 is a fragmentary sectional view taken on the line 11—11 of Figure 10.

Referring in detail to the drawings, the numeral 5 indicates a lathe of a conventional construction including the usual tool holder 6. An electric armature 1 is shown as supported by the 55

lathe, the commutator of which is indicated by the character 8. It is a well known fact that after an electric armature has been in use for a period of time the bars 9 of the commutator 8 become worn or pitted so that the brushes of the motor or generator of which the armature forms a part fail to ride evenly and smoothly on the commutator. Therefore, the bars must be turned down to bring the commutator 8 in proper condition to be engaged by the brushes. In the reconditioning of the bars they are cut away by a suitable tool and after this reconditioning operation it is necessary that the insulation also be cut away to deepen the grooves between the bars and to remove any abrasions or particles that may be on the side faces of the bars. To permit this further reconditioning operation to be quickly and accurately carried out the present invention is employed which also, by adapting thereto a proper cutter or tool, may be employed for the initial reconditioning or turning down of the brush faces of the bars.

To adapt the present invention to the lathe the usual tool post of the tool carriage 6 is removed and a post 10 substituted in lieu thereof. This post 10 assumes a vertical position on the tool carriage 6 and has a groove 11 and a head 12 to fit in the usual notch 13 of the tool carriage 6 and to be held therein by a clamping nut 14 threaded on the post 10.

Mounted for vertical adjustment on the post 10 is a split sleeve 15 having stud bolts 17 for clamping the sleeve in adjusted positions on the post. It will be seen that the sleeve 15 besides being 35 adjustable vertically on the post 10 may also be adjusted in a rotatable manner on said post.

Formed on the sleeve 15 is a horizontally disposed split sleeve 18 for slidably supporting a cutter carrying plunger 19. The sleeve 18 has 40 stud bolts 20 whereby the grip of the sleeve on the plunger 19 may be increased and decreased as desired.

The plunger 19 is provided with a slot 21 in which is clamped the shank of a cutter 22 by a 45 set screw 23. This cutter is for the purpose of cutting the insulation between the bars 9 and the commutator and thereby bring the grooves between the bars to a proper depth.

Should it be desired to recondition the faces of the bars of the commutator another tool is substituted in lieu of the tool 22.

A hand lever 24 is pivoted to the plunger 19 and its fulcrum is indicated at 25. The plunger 19 may be reciprocated by the hand lever to move the cutting tool parallel to the bars 9 within

the grooves of the commutator for cutting the insulation. The fulcrum 25 is in the form of a link 26 pivoted the lever 24 and to the sleeve 15 by using one of the stud bolts.

A bracket 27 is supported on the sleeve 18 by the stud bolts 20 and carries a bolt 28 which also extends through a bearing 29 of a spacer 30. The spacer 30 besides including a finger piece 31 also includes a groove engaging end 32. The spacer is substantially L-shaped, as shown in Figure 6, one portion of which is provided with slots 33 to receive the fasteners 34 of the bearing 29 permitting the spacer to be adjusted toward and from the tool 22 so that the device may be made to operate successfully in connection with commutators wherein the distances between the grooves vary.

The end 32 of the spacer is adapted to ride into and out of the grooves of the commutator as the armature 7 is rotated on the lathe and when in engagement with a groove will position the commutator so that another groove will be in proper position to be acted on by the tool 22 during the reciprocation of the plunger 19.

It is to be understood that the bearing 29 and its fasteners 34 provide a construction which will frictionally grip the spacer to hold the same against accidental movement but which will permit the end 32 to ride into and out of the grooves of the commutator as the armature is rotated due to the flexibility of the spacer.

Referring to my modified form of the invention, the major construction of which is substantially the same as the form heretofore described in detail and the principal difference residing in the fact that the tool post sleeve 34 has the plunger sleeve 35 slidably mounted thereon whereby the sleeve 35 may be adjusted vertically for the purpose of regulating the depth the groove is cut in the commutator by the tool.

An adjusting stem 36 is threaded in the sleeve 35 and is journaled on the sleeve 34 whereby the sleeve 35 may be adjusted vertically with respect to the sleeve 34 for varying the depth of the cut made by the tool of the plunger.

While I have shown and described the pre-

ferred embodiment of my invention, it will be understood that minor changes in construction, combination and arrangement of parts may be made without departing from the spirit and scope of the invention as claimed.

Having thus described my invention, what I claim is:

1. Reconditioning apparatus for use on the tool holder of a lathe and to regroove the commutator of an armature rotatably mounted in the lathe, said apparatus comprising a post adapted to be secured to said holder in upright position, a sleeve vertically adjustable on said post into different set positions and having a second sleeve fixed thereon at a right angle thereto, a tool holding plunger endwise slidable in the second-mentioned sleeve, a tool detachably mounted on said holder, manipulative means for sliding said plunger, and means on said second sleeve for holding the commutator in different angular positions and constructed and arranged to yieldingly engage the grooves in the commutator under rotation of the latter into different angular positions.

2. Reconditioning apparatus for use on the tool holder of a lathe and to regroove the commutator of an armature rotatably mounted in the lathe, said apparatus comprising a post adapted to be secured to said holder in upright position, a sleeve vertically adjustable on said post into different set positions and having a second sleeve fixed thereon at a right angle thereto, a tool holding plunger endwise slidable in the second-mentioned sleeve, a tool detachably mounted on said holder, manipulative means for sliding said plunger, and means on said second sleeve for holding the commutator in different angular positions and constructed and arranged to yieldingly engage the grooves in the commutator under rotation of the latter into different angular positions, said last means comprising a right angled member of resilient metal and including a finger piece and a groove engaging end, the member being mounted on the second sleeve for rotary setting and to variably tension the groove engaging end against the commutator.

ADOLPH L. BAURHENN.
